CONTAINER

Ronald I. Drake, Appleton, Wis., assignor to Marathon Paper Mills Company, Rothschild, Wis., a corporation of Wisconsin

Application February 11, 1935, Serial No. 5,926

10 Claims. (Cl. 229—5.5)

This invention is directed to the means provided for binding and reinforcing the rim of a substantially cylindrical container intended primarily, but not exclusively, for the shipment of 5 ice cream in bulk. Containers of this type are constructed of relatively stiff paper-board, and are designed ordinarily for a single service, and such a container requires the use of a metal reinforcing strip for the upper rim or margin in 10 order to stiffen the container and hold it properly distended.

The present invention is directed to the form and construction of such a binding strip and means for securing it firmly and tightly in place. 15

Further objects and details will appear from a description of the invention in conjunction with the accompanying drawing, wherein:—

Figure 1 is a perspective view of a container embodying the features of the present invention; 20 Fig. 2 is a sectional detail taken on line 2—2 of Fig. 1;

Fig. 3 is a sectional detail taken on line 3—3 of Fig. 2; and

Fig. 4 is a perspective detail of a fragment of 25 the binding strip.

The container is formed to provide a substantially cylindrical wall 10 formed of paper-board which may be truly cylindrical or slightly tapered, as shown, and of sufficient thickness and stiffness to afford an enclosure for several gallons of 10 ice cream, or the like. It will be understood, however, that although the present invention is especially adapted to reinforcement of relatively large containers, it can be applied with like advantage to containers of smaller size.

The container around its upper rim or margin is provided with a metallic binding strip which is bent to afford an outer lip 11, an inner lip 12, and a bend or fold 13 which arches over the 15 upper edge of the container wall. As shown, the outer lip is of greater vertical width than the inner lip which latter is provided with vertically extending crimps or corrugations 14 each of which extends from a point slightly below the bend 13 to a point slightly above the lower edge of the lip, leaving the lower edge smooth or un-crimped to bear closely against the circumferential surface of the wall 10. The crimps or corrugations 14 may, if desired, extend to the lower 20 edge of the rim.

The outer lip is provided with an outwardly extending bead 15 affording a circumferential rib, and is also provided below the bead at recurrent intervals with inwardly extending burred 25 bosses 16 which are formed by punching the

metal of the strip to afford apertures, displacing the metal inwardly at an abrupt angle to provide the bosses mentioned which surround the apertures and are adapted to bite into the surface 5 of the wall. The strip thus formed constitutes a binding hoop for the upper edge of the paper-board wall and is applied thereto by spreading the lips sufficiently, as in Fig. 4, to permit the hoop to be slipped on to the upper rim of the container, after which the hoop above and below the bead is subjected to a rolling or crimping action which serves to tightly press together the lips and cause the burred bosses to pierce into the surface of the container wall, and also causes the corrugations 14 to impinge tightly, or, upon 15 application of sufficient pressure, to imbed themselves slightly into the inner surface of the container wall. This insures a tight, firm grip upon the paper-board surface and at the same time the gripped or corrugated formation of the inner 20 lip affording sufficient stiffness to the structure to prevent the lips from spreading apart when relieved from the gripping pressure, so that after the hoop is set in place it will retain its 25 shape and thus serve as a stiffening and reinforcing member for the rim of the container.

The crimping or corrugating of the inner lip is also of advantage in giving to the hoop the cylindrical form required in that the crimping operation serves to take up the surplus metal 30 present by reason of the reduced radius of curvature of the inner lip as compared with the outer lip, and the stiffness afforded by the corrugations not only prevents the spreading of the lips when forced into gripping relation to one another, but 35 also affords the stiffness required to maintain the circular configuration of the container. This stiffness is also increased by the circumferential bead which being medially located does not interfere with the rolling or crimping of the hoop 40 required in fastening it to the rim of the container.

Although the invention is particularly adapted for use in the reinforcement of containers of the class described, the binding strip or hoop 45 of the present invention is well adapted for other uses in which it is desirable to provide a metal reinforcement for the edge of a fibrous sheet or wall, so that it will be understood that it is not the intention, unless otherwise indicated in the 50 claims, to strictly limit the invention to the particular use shown and described.

I claim:

1. In a container, the combination of a curving wall of fibrous material and a metallic hoop 55

- secured to the rim of the wall, the hoop comprising inner and outer lips in contacting relation to the inner and outer surfaces of the wall, and a connecting bend overlapping the edge of the wall, 5 one of the lips being provided with inwardly extending bosses impinging into the adjacent surface of the container wall and the other lip being provided with vertical stiffening corrugations extending from points above its uncorrugated edge 10 and toward the bend and adapted to hold the two lips in biting relation to one another.
2. In a container, the combination of a curving wall of fibrous material and a reinforcing hoop therefor comprising inner and outer lips 15 in spaced relation to one another and connected by a bend, the outer lip being provided with a plurality of inwardly extending burred bosses impinging into the surface fibers of the container wall, and the inner lip being provided with vertical corrugations extending from points slightly 20 above its uncorrugated edge to points closely adjacent the bend and adapted to impinge against the inner surface of the container wall and hold the burred bosses in impinging relation and to stiffen and reinforce the container.
3. In a container, the combination of a curving wall of fibrous material and a metallic hoop secured to the rim of the wall, the hoop comprising inner and outer lips in contacting relation to 30 the inner and outer surfaces of the wall, and a connecting bend overlapping the edge of the wall, one of the lips being provided with inwardly extending bosses impinging into the adjacent surface of the container wall and the other lip being 35 provided with stiffening corrugations adapted to hold the two lips in biting relation to one another, the lip with the bosses being also provided with an outwardly extending circumferential bead furnishing a reinforcing rib.
4. In a container, the combination of a curving wall of fibrous material and a metallic hoop secured to the rim of the wall, the hoop comprising inner and outer lips in contacting relation to the inner and outer surfaces of the wall, 45 and a connecting bend overlapping the edge of the wall, one of the lips being provided with inwardly extending bosses impinging into the adjacent surface of the container wall and the other lip affording the necessary resistance to hold the 50 bosses in impinging relation, the lip with the bosses being also provided with an outwardly extending circumferential bead furnishing a reinforcing rib.
5. In a container, the combination of a curving wall of fibrous material and a metallic hoop secured to the rim of the wall, the hoop comprising inner and outer lips in contacting relation to the inner and outer surfaces of the wall, and a connecting bend overlapping the edge of the wall, 55 the outer lip being provided with inwardly extending bosses impinging into the adjacent surface of the container wall and the inner lip being provided with stiffening corrugations adapted to hold the two lips in biting relation to one another, and the outer lip being also provided with an outwardly struck circumferentially extending bead furnishing a reinforcing rib.

6. In combination with a fibrous wall, a metallic binder having inner and outer lips and a connecting bend embracing the edge of the wall with the lips in contact with the opposite surfaces of the wall, one of the lips being provided with inwardly extending bosses and the other lip bearing closely against the opposite surface of the wall to hold the bosses in impinging relation to the surface of the wall, the lip with the bosses being also provided with an outwardly extending circumferential bead furnishing a reinforcing rib. 10

7. In combination with a fibrous wall, a metallic binder having inner and outer lips and a connecting bend embracing the edge of the wall 15 with the lips in contact with the opposite surfaces of the wall, one of the lips being provided with inwardly extending bosses and the other lip bearing closely against the opposite surface of the wall to hold the bosses in impinging relation 20 to the surface of the wall, the lip with the bosses being also provided with a continuous circumferential bead outwardly struck along a medial line and above the bosses and serving to reinforce the lip. 25

8. In combination with a fibrous wall, a metal binder having inner and outer lips and a connecting bend embracing the edge of the wall with the lips in contact with the opposite sides of the wall, 30 one of the lips being provided with vertical stiffening corrugations extending from points above its uncorrugated edge and toward the bend and the other lip bearing closely against the opposite surface of the wall to hold the corrugations in 35 impinging relation to the proximate surface of the wall. 40

9. In combination with a fibrous wall, a metal binder having inner and outer lips and a connecting bend embracing the edge of the wall with the lips in contact with the opposite sides of the wall, 45 one of the lips being provided with vertical stiffening corrugations extending from points above its uncorrugated edge and toward the bend and the other lip bearing closely against the opposite surface of the wall to hold the corrugations in 50 impinging relation to the proximate surface of the wall, and the last-named lip being provided with an outwardly struck longitudinally extending bead furnishing a reinforcing rib. 45

10. In combination with a fibrous wall, a metal binder having inner and outer lips and a connecting bend embracing the edge of the wall with the lips in contact with opposite surfaces of the wall, 55 one of the lips being provided with inwardly extending bosses formed by punching the lip to afford apertures surrounded by abruptly inwardly protruding burrs adapted to bite into the fibrous wall and the other lip bearing closely against the opposite surface of the wall to hold the bosses in 60 impinging relation to the surface of the wall, said first lip being provided with an outwardly struck longitudinally extending bead furnishing a reinforcing rib. 65
